FORK OR SIMILAR ARTICLE OF FLATWARE

Magnus L. Stephensen, Copenhagen, Denmark

Application May 15, 1956, Serial No. 41,497

Term of patent 14 years

(Cl. D54—12)

Figure 1 is a top plan view of a fork or similar article of flatware illustrating my design;

Figure 2 is a side elevational view thereof;

Figure 3 is a sectional view taken substantially along the line 3—3 of Figure 1;

Figure 4 is a sectional view taken substantially along the line 4—4 of Figure 1; and

Figure 5 is an end view of the tip of the handle.

The back of the handle is smooth and of a convex curvature complementing the concave curvature of the front, as particularly shown in Figures 3, 4 and 5.

The characteristic feature of the article resides in the portion shown in full lines of the drawing wherein the handle is of substantially arcuate cross-sectional configuration which extends and flows down into the bowl as shown.

I claim:

The ornamental design for a fork or similar article of flatware as shown and described.
